Primary Examiner — Melanie H Tung*Assistant Examiner* — Bao-Yen T Nguyen(74) *Attorney, Agent, or Firm* — William J. Clemens; Shumaker, Loop & Kendrick, LLP(57) **CLAIM**

The ornamental design for a display screen with icon, as shown.

DESCRIPTION

FIG. 1 is a front view of a display screen with icon showing our new design; and,

FIG. 2 is a front view of a second embodiment of the display screen with icon showing our new design.

The broken lines showing the display screen form no part of the claimed design.
